UNITED STATES PATENT OFFICE.

FREDERICK N. CRONHOLM, OF ANDRADE, CALIFORNIA.

CONSTRUCTION OF DAMS.

Application filed April 21, 1921. Serial No. 463,141.

To all whom it may concern:

Be it known that I, FREDERICK N. CRONHOLM, a citizen of the United States, residing at Andrade, in the county of Imperial 5 and State of California, have invented a new and useful Improvement in the Construction of Dams, of which the following is a specification.

This invention has reference to the construction of dams, and its object is to provide an economical plan whereby dams may be constructed in rivers or breaks in levees may be closed.

The invention contemplates the employment of wedge-shaped bundles or mattresses which may be of buoyant form and which, when subjected to the flow of a stream, so that the water will engage the thin edge of the wedge, and the wedge is held at an appropriate angle, will cause the wedge to dive and ultimately rest upon the bottom of the stream where it is held by the flow of water until sand or silt gathers upon the mattress and weights it down to ultimately anchor it in place.

By the employment of a suitable number of the wedge shaped mattresses, the dam may be built up by the action of the stream until the desired height of dam, and consequent depth of water, is obtained.

The invention will be best understood from a consideration of the following detailed description taken in connection with the accompanying drawings forming part 35 of this specification, with the understanding, however, that the invention is not confined to any strict conformity with the showing of the drawings, but may be changed and modified so long as such changes and modifications mark no material departure from the salient features of the invention as expressed in the appended claims.

In the drawings:

Fig. 1 is a more or less schematic view of an actual installation of the invention.

Fig. 2 is a cross section through a river bed showing, more or less schematically, the same installation.

Fig. 3 is a longitudinal view in section, 50 of the river bed showing the placing of the mattresses and the manner of anchoring the same.

Fig. 4 is a plan view of one of the mattresses.

Fig. 5 is a side view thereof.

Fig. 6 is a plan view of a bottom frame on which the mattress is built up.

Fig. 7 is an end view of the larger end of the mattress.

In Figs. 4, 5, 6 and 7, no attempt is made 60 to show any particular proportions for such proportions may vary within wide limits. From the practical point of view, the invention has been tried out on the Colorado River, and has proven successful in closing 65 the stream where it is from 15 to 20 feet deep and approximately 800 feet wide.

In carrying out the invention, a suitable number of mattresses A are employed, which mattresses are made up of longitudinal 70 beams 1 and cross beams 2, constituting top and bottom frames, each of which has the longitudinal and cross beams secured together in any appropriate manner, as by spikes or bolts 3, together with ropes or 75 cables 4, with an interior filling between the frames of bundles 5, which may be composed of brush or similar material. The top and bottom frames are arranged at an angle to each other, so that they define a wedge of 80 considerable height at one end and approaching to an approximate point or edge at the other end.

The wedges or bales of brush and timbers in the actual installation each approximate 85 10 feet wide, 14 feet high at the back or downstream end, and from 27 to 30 feet long, but it is to be understood that these figures are not at all mandatory. The top and bottom frames that confine the bundles of brush 90 together may be constructed of 8 inch round timbers, while the bundles of brush composing the mass are stacked crosswise and lengthwise in alternate layers or in any other 95 manner which will give the most compactness for the size required, and then the whole mass is made more compact by pressure on the top and bottom frames, which are fastened with steel cable.

There are also employed an appropriate 100 number of dolphins 6, composed of groups of piles driven into the bed of the river, with each dolphin embraced by a suitable number of loops 7 formed in cables 8, which cables extend from the loops 7 to a point 9 105 about midway of the length of a dam element or bale A on the upper or inclined surface thereof, so that when the wedge-shaped

bale is floating on the surface of the stream represented at 10, the force exerted upon the bale is that due to the flotation of the bale A and the pull on the bale due to the force of flow of the stream, resulting in the depression of the point or edge of the bale which is upstream below the surface of the stream, whereby the tendency of the resultant forces is to cause the bale to dive to the bottom of the stream represented at 11 in Fig. 3. This diving force is constantly exerted due to the continued flow of the stream and the bale is held firmly against the bottom of the stream in opposition to the buoyancy of the bale, while the surface of the stream is diverted into a wave 12 (see Fig. 3) contributing to the holding of the bale on the bottom of the stream, so that sand or silt present in the stream lodges in the interstices of the bale to ultimately fill them and thereby automatically weight the bale until it becomes heavier than the water displaced thereby and so remains anchored on the bottom of the stream irrespective of, though aided by, the cable 8.

In Fig. 3, there is indicated a barge 13 equipped with suitable machinery for driving the piles making up the dolphins 6, and for placing the loops 7 of the cables 8 over the dolphins to anchor the mattresses against the force of the down flow of the stream. In order to anchor the barge in any position crosswise of the machine, there is provided an overhead cableway 14 suspended from towers 15 on opposite banks of the stream. Further down stream, so as to carry the assembled brush elements A into position, is another cableway 16 crosswise of the stream and supported from towers 17. The cable 16 is shown in Fig. 2 as carrying a trolley 18 with a brush element A dependent therefrom.

There is also indicated in Fig. 1 a discharge pipe 19, which may be considered as leading from a suction dredge, the pipe 19 discharging into the stream or over the fill near the bank of the stream and in the upstream direction from the sunken dam elements A.

One advantage of the invention is that one or more of the units may be employed to dam back the waters of a stream or canal or the waters of a large river, or for the purpose of training the channels in predetermined directions. The units are preferably buoyant, and are, therefore, capable of being easily handled or floated to position. The unit may be in effect a shell containing brush or other like waste material having the quality of floating and assembled in wedge or similar angular shape with the inclined upper surface an essential part, and the attachment of the lines or cables so arranged that the force of the flowing stream operating on the wedge or inclined surface

causes the depression of the dam units to the bottom of the stream, where they will accumulate silt or sand or other heavy material carried by the stream and tending to overcome the buoyancy of the normally floating unit. 70

The essential parts of the unit are the inclined upper surface, the anchor cable and its position and connection to the dam element at an intermediate point of its length. 75 This causes the wedge shape unit to incline downwardly toward the upstream end, the high end of the dam element being downstream. The use of brush has an advantage in that silt will deposit in the interstices, 80 thereby helping in the building of the dam and, moreover, the use of brush lessens the cost of building, since it is usually a waste material to be obtained in plentiful quantities, either on the shores of the stream or 85 closely adjacent thereto.

A single anchorage cable is ample and no weight need be added to sink the units in the water, the river flow immediately causing the automatic sinking upon immersion 90 because of the position of the anchorage which causes the upstream end to dip downwardly as though the element were pivoted to the anchorage. In cases where an aerial cableway is available, no false work or obstruction in the water is needed and the damming back of the stream is not necessary until the time that such obstruction is actually required. The anchorage posts or dolphins are spaced apart 100 feet 100 or more and the relatively great separation of these dolphins does not constitute an obstruction to the stream. Again, the manner of sinking the bundles or units does not require that the stream be by-passed during the period when the bundles are being placed.

While the unit or mattress is caused to sink, though normally buoyant, and is kept submerged by the force of the flow of the 110 stream against it due to the manner of anchorage, the unit cannot submerge deeper than the river bottom against which it is held, because of the manner of attachment of the anchorage cable thereto. 115

This application is specific to a wedge-shaped dam element which is the preferred form of my invention. In another application filed March 14th, 1922, Serial No. 543707, I have disclosed various modified forms and have embraced in said application generic claims which cover the dam element in any form wherein a flat side or face is present. 120

What is claimed is:—

1. In dam construction, wedge-shaped dam elements, anchoring means in upstream spaced relation to the dam site, and connections from the anchoring means to each wedge-shaped element connected to the up- 130

per surface of the latter intermediate of its length, with the thin end of the wedge directed upstream.

2. In dam construction, dolphins rising from the bed of the stream and spaced upstream from the location of the dam, wedge-shaped dam elements with the thin edge of the wedge directed upstream, and cables having loops secured to the dolphins and 10 also secured to the dam elements intermediate the length thereof, whereby the velocity of the stream acting upon the inclined faces of the dam elements tends to depress the elements in opposition to the buoyancy there- 15 of until said elements are arrested by the bed of the stream.

3. In dam construction, a wedge-shaped

dam element formed of top and bottom skeleton frames, and a filling of brush or the like, dolphins rising from the bed of the stream and spaced upstream from the location of the dam, and cables secured to the dolphins and to the wedge surfaces of the dam elements intermediate of the length of the elements whereby the thin end of the wedge is presented upstream and the wedge-shaped element is held at an angle to cause the sinking of the element by the velocity of the flowing stream.

In testimony, that I claim the foregoing 30 as my own, I have hereto affixed my signature.

FREDERICK N. CRONHOLM.
